UNITED STATES PATENT OFFICE.

ALEXANDER BOGDANSKI, OF COHOES, NEW YORK.

TROLLEY SWITCH.

Application filed September 27, 1922. Serial No. 590,986.

To all whom it may concern:

Be it known that I, ALEXANDER BOGDANSKI, a citizen of Poland, residing at Cohoes, in the county of Albany and State of New York, have invented new and useful Improvements in Trolley Switches, of which the following is a specification.

Reference may be had to the accompanying drawings, and the reference characters marked thereon, which form a part of this specification. Similar characters refer to similar parts in the several figures therein.

The principal object of the invention is to facilitate the passage of a trolley over or past a switch.

Other objects will appear in connection with the following description.

Fig. 1 of the drawings is a top plan view of the switch with the line-wires and switch-plate-supporting cables broken-away.

Fig. 2 is a bottom plan view of the same showing the position of the trolley-wheel entering the switch from the right-hand member of two divergent rails leading from the neighboring end of the switch.

Fig. 3 is a section partly in side elevation and partly in vertical longitudinal section of the same.

Fig. 4 is a cross-section of the same taken on the broken line 4—4 in Fig. 2.

Referring to the drawings wherein the invention is shown in preferred form, 1 is a trolley-switch-plate adapted to be supported by transverse cables, 2, from poles or other supports on opposite sides of the railway way in the usual manner, said poles or supports being not shown.

At one end of the switch-plate, 1, are a pair of rails, 3, 4, adapted to be engaged and traversed by a grooved trolley-wheel 5. These rails, 3, 4, may be connected with line-wires, 6, in any known manner, and are preferably connected with the line-wires in such a manner that the ends of the wires are flush with the trolley-engaged surfaces of the rails, 3 and 4.

At the other end of the switch-plate, 1, is a rail, 7, similar to the rails, 3 and 4, and connected in a similar manner with the line-wire, 8.

The rail, 7, terminates in a tongue, 9,

pivoted at 10, upon the switch-plate, 1, the swinging end of said tongue being alinable with the inner ends of the divergent rails, 3 and 4, alternatively as indicated by dotted lines in Fig. 2.

The tongue, 9, is normally controlled by a spring, 11, connected with a pin, 12, fixed upon the swinging end of the tongue and playing in a slot, 13, in the switch-plate whereby the tongue is normally held in mid-position between the neighboring ends of the rails, 3 and 4, as shown by solid lines in Fig. 2.

The inner end of the tongue, 9, and the inner ends of the rails, 3 and 4, are beveled as shown at 14, whereby the passage of the trolley-wheel from the tongue to one of the rails, 3 and 4, or the passage of the trolley-wheel from one of the rails, 3 and 4, to the tongue is facilitated.

The several rails, 3, 4, and 7, and the tongue, 9, are formed with side grooves, 15, as shown more particularly in Fig. 4, which grooves are adapted to be engaged by pins, 16, projecting inwardly from the members of the yoke, 17, within which the trolley-wheel, 5, is rotatively mounted, said yoke being at the upper end of the trolley-pole, 18, as is customary.

The pins, 16, are carried by the respective spring-plates, 19, attached to the outer sides of the members of the yoke, 17, whereby the pins are yieldingly mounted and adapted to move toward and from each other.

I have shown a trolley-cord, rope or cable, 20, connected with the trolley-pole, 18, for controlling the pole in applying the same to the line-wires or the switch-rails or tongue.

The operation of the mechanism is as follows:

In passing into the switch from either direction, as electric railways are usually laid out, the car swerves to the right, thus tending to cause the trolley to deflect to the right; and in passing from a switch to the main line, the car usually enters the switch with the trolley in engagement with the right-hand member of the two convergent line-members, 6.

Thus, in entering the switch from the end

having the divergent, or convergent, rails, 3, 4, the trolley-wheel would traverse the rail, 3, as in Fig. 2, until the beveled end of the tongue, 9, is engaged by the groove 5 of the trolley-wheel, whereupon the tongue, 9, would be forced by the trolley-wheel into substantial alinement with said rail, 3, and the trolley would have a substantially continuous path from the rail, 3, over the 10 tongue, 9, to the rail, 7.

In entering the switch from the opposite direction the trolley-wheel, due to the swerve of the car, would be deflected or inclined toward the rail, 4, in its path over the 15 tongue, 9, causing the tongue to be brought into substantial alinement with the rail, 4, and thus to afford a substantially continuous path from the tongue to the rail, 4.

During the passage of the trolley-wheel 20 over or through the switch in either direction, the tendency of the trolley-wheel to jump downward in passing the gap between the neighboring ends of the tongue, 9, and the rails, 3, 4, is overcome by engagement 25 of the pins, 16, with the side grooves, 15, in either the rail or the tongue over which the trolley-wheel is moving forwardly.

The pins, 16, are mounted upon the trolley-yoke, 17, so that they engage the side 30 grooves in the rails, 3, 4, or tongue, 9, at a point in rear of that at which the trolley-wheel engages the respective tongue or rail, so that at the time when the trolley-wheel 35 is crossing the gap, 21, between the neighboring ends of the tongue and the rails, 3, 4, in either direction, downward movement of the trolley-pole is prevented by engagement 40 of the pins, 16, with the side grooves, 15, in the tongue or one of the rails, 3, 4, as the case may be.

What I claim as new and desire to secure by Letters Patent is—

1. The combination with a trolley-switch having a switch-plate, a rail leading from 45 one end of the switch-plate terminating at its inner end in a pivoted tongue; and a pair of divergent rails leading from the other end of the switch-plate, said tongue being alinable with the inner ends of said 50 divergent rails alternatively, said rails and tongue being provided with side-grooves; of a trolley-wheel grooved to traverse said rails and tongue; and a trolley-wheel-support having projections engageable with the side- 55 grooves in said rails and tongue.

2. The combination with a trolley-switch having a switch-plate, a rail leading from one end of the switch-plate terminating at its inner end in a pivoted tongue, and a pair 60 of divergent rails leading from the other end of the switch-plate, said tongue being alinable with the inner ends of said divergent rails alternatively, said rails and tongue being provided with side-grooves; of a trolley-wheel-support having projections en- 65

gageable with the side-grooves in said rails and tongue rearwardly of the point of engagement of the trolley-wheel with said rails and tongue.

3. The combination with a trolley-switch 70 having a switch-plate, a rail leading from one end of the switch-plate terminating at its inner end in a pivoted tongue, and a pair of divergent rails leading from the other end of the switch-plate, said tongue being alinable with the inner ends of said divergent rails alternatively, said rails and tongue being provided with side-grooves; of a trolley-wheel grooved to traverse said rails and tongue; and a trolley-wheel-support having 80 yielding pins engageable with the side-grooves in said rails and tongue rearwardly of the point of engagement of the trolley-wheel with said rails and tongue.

4. The combination with a trolley-switch 85 having a switch-plate, a rail leading from one end of the switch-plate terminating at its inner end in a spring-controlled tongue; and a pair of divergent rails leading from the other end of the switch-plate, said tongue being alinable with the inner ends of said divergent rails alternatively, said rails and tongue being provided with side-grooves; of a trolley-wheel grooved to traverse said rails and tongue; and a trolley-wheel-support 95 having projections engageable with the side-grooves in said rails and tongue.

5. The combination with a trolley-switch having a switch-plate, a rail leading from one end of the switch-plate terminating at its inner end in a spring-controlled tongue, and a pair of divergent rails leading from the other end of the switch-plate, said tongue being alinable with the inner ends of said divergent rails alternatively, said rails and tongue being provided with side-grooves; of a trolley-wheel grooved to traverse said rails and tongue; and a trolley-wheel-support 100 having yielding pins engageable with the side-grooves in said rails and tongue.

105

6. The combination with a trolley-switch having a switch-plate, a rail leading from one end of the switch-plate terminating at its inner end in a pivoted tongue, and a pair of divergent rails leading from the other end of the switch-plate, said tongue being alinable with the inner ends of said divergent rails alternatively, said rails and tongue being provided with side-grooves; the neighboring ends of said divergent rails and tongue being beveled; of a trolley-wheel grooved to traverse said rails and tongue; and a trolley-wheel-support having projections engageable with the side-grooves in 110 said rails and tongue.

115

7. The combination with a trolley-switch having a switch-plate, a rail leading from one end of the switch-plate terminating at 120

125

130

its inner end in a spring-controlled tongue, and a pair of divergent rails leading from the other end of the switch-plate, said tongue being alinable with the inner ends of said divergent rails alternatively, said rails and tongue being provided with side-grooves, the neighboring ends of said divergent rails and tongue being beveled; of a trolley-
wheel grooved to traverse said rails and tongue; and a trolley-wheel-support having 10 projections engageable with the side-grooves in said rails and tongue.

In testimony whereof, I have hereunto set my hand this 26th day of September, 1922.

ALEXANDER BOGDANSKI.
